PROPANE DEWAXING

Henry O. Forrest, Teaneck, and Lee Van Horn,
Elizabeth, N. J., assignors to Standard Oil Com-
pany, Chicago, Ill., a corporation of Indiana

Application June 30, 1934, Serial No. 733,258

7 Claims. (Cl. 196—18)

This invention relates to an improved method and means for applying auto-refrigeration to useful purposes and it pertains more particularly to an improved propane dewaxing system.

5 It has been found that liquefied, normally gaseous hydrocarbon diluents such as propane offer many extremely important advantages in the dewaxing of mineral oils. Such diluents permit or cause the crystallization of wax in readily filterable or settleable form even though the wax is of such nature that it could not be commercially filtered or settled from ordinary naphtha diluents. Also, it has been found that rapid chilling rates 10 may be employed, that high yields of low pour 15 point oils (relatively dry wax cakes) are obtained, that extremely rapid filtration or settling can be used, and that removal of diluent from dewaxed oil actually supplies refrigeration to the system and requires a minimum amount of heat and 20 stripping steam.

An object of our invention is to provide an improved method and means for cooling a propane-oil-wax mixture to extremely low temperatures without "shock chilling" and without employing 25 unduly large quantities of propane. A further object is to control the cooling and crystallization 30 of wax, so that it will yield a dense and relatively dry wax cake and a maximum yield of dewaxed, low pour point oil.

35 Normally gaseous diluents such as propane have also been found to have unique properties in the deasphalting of petroleum residues and/or in the fractionation thereof into components of higher and lower average molecular weights. These same diluents have been found to be extremely useful 40 in combination with solvents for separating high viscosity index or paraffinic fractions of oil from low viscosity index naphthenic fractions. An object of our invention is to provide a chilling system that will be useful in these processes.

45 A further object is to utilize effectively the large amount of refrigeration which is available in the step of removing propane from propane-oil solutions. Other objects will be apparent as the detailed description of our invention proceeds.

In applying our invention to propane dewaxing, we introduce measured amounts of propane and 50 charging stock into a mixing chamber to obtain a homogeneous mixture or solution of the waxy oil in the propane. This mixture may then be cooled to approximately its cloud point by ordinary cooling water and it may be further cooled by indirect heat exchange with cold filtrate. The amount of refrigeration which can be employed in 55 this manner is somewhat dependent upon the

nature of the wax which is undergoing separation and if the scrapers employed in the heat exchange apparatus tend to break up the wax crystals and interfere with the later mechanical separation step, we may avoid the indirect heat exchange entirely and obtain all of the cooling by direct refrigeration.

An important feature of this invention is the method of introducing cold propane into the chill chamber to replace the propane vaporized therefrom. We prefer to introduce cold propane at about -40° F. because wax-free propane may be readily cooled by heat exchange with the cold filtrate. If this cold propane were introduced directly into a body of warm waxy oil solution 15 there would be a shock chilling which would result in the formation of fine amorphous, non-filterable and non-settleable wax crystals.—we therefore introduce the cold propane above the body of the propane-oil mixture in the chilling 20 tank and we contact this cold propane with vaporized propane in the upper part of the chamber before the cold propane comes in contact with the waxy solution. This contact in the upper part 25 of the chamber is preferably effected on bubble trays of the type used in the fractionating towers of a distillation system, but any equivalent gas liquid contact means may be substituted therefor. The condensation of warm propane vapors in the 30 newly added cold propane tends to warm up the cold propane, so that by the time it reaches the liquid body at the base of the chiller it is at substantially the same temperature as that body. At the same time propane vapors are removed 35 from the upper part of the chiller in amounts regulated to obtain the desired rate of cooling and the introduction of cold propane is regulated to serve as a reflux liquid, to maintain the desired propane concentration in the waxy oil propane 40 solution, to accomplish the necessary refrigeration, and finally to reduce the viscosity of the chilled oil, so that it may be readily filtered or settled from the solidified wax. By introducing the cold propane at the top of the chiller and by passing it over one or more bubble plates we obtain chilling with a minimum amount of propane 45 and we maintain an extremely efficient and accurate method of controlling the temperature and the rate of chilling.

This invention is particularly useful for the removal of paraffinic waxes which have a tendency to form interlacing crystals and to occlude oil. So-called "pour point depressors" have been found to regulate wax crystallization and their presence makes it possible to obtain denser wax 55

5 cakes and higher oil yields than would be possible under the same conditions without the pour point depressors. We have found that the oil itself contains crystallization regulators which are effective when only small amounts of propane are employed in the chilling step, but which are less effective when large amounts of propane are present during the crystallization of the wax. In accordance with our invention it is possible to 10 crystallize the wax by auto-refrigeration in the presence of less than one volume of propane per volume of oil and we have found that this tends to give wax crystals that do not occlude appreciable amounts of oil; it tends to give large oil 15 yield and dense wax cakes, particularly when the wax is of the crystalline type. We obtain all of the advantages of large propane volumes without their disadvantages and at the same time we obtain the benefit of "pour point depressors" in 20 the oil itself. Additional cold propane may be added to the slurry just before the filtration or settling step, but we avoid long standing of crystallized wax in propane solution; the wax is not very soluble in propane at dewaxing temperatures but long standing may result in deleterious 25 re-arrangement of crystal formation.

In propane deasphalting the injection of extremely cold propane may cause the solidification of portions of the asphalt in combination with the 30 oil or, in other words, it causes the occlusion of oil in solidified asphalt. By employing our improved method and means for adding propane to the system, the propane is at substantially the same temperature as the asphaltic oil before it comes in 35 contact with said oil and it therefore produces an oil solution which may be readily separated from the insoluble asphalt phase. The introduction of propane in accordance with our improved method facilitates the subsequent phase separation with 40 a minimum amount of propane.

In the accompanying drawing we have shown a diagrammatic elevational plan of our improved propane dewaxing system.

The term "propane" as used herein is expressly 45 defined to cover equivalent normally gaseous diluents and particularly hydrocarbons of from two to four or five carbon atoms and mixtures thereof. In other words, this expression is intended to include butane, ethane, propylene, butylene, etc. and mixtures thereof either alone or in combination with halogenated substitution 50 products of methane and ethane, normally gaseous ethers, sulfur dioxide, methyl amine, etc. This invention relates to the technique of employing normally gaseous diluents and it is not dependent upon the use of any specific diluent.

The invention may be employed for the dewaxing of any wax-bearing oil, but it is particularly useful in the dewaxing of petroleum distillates or petroleum residues from which asphalt has been separated. The invention is also useful on residual stocks containing asphalt, particularly when the asphalt itself acts as a filter aid or settling aid and helps to carry down the wax in 65 readily separable form. The invention is not limited to dewaxing, but may be employed for the deasphalting of petroleum residua or for the cooling of hydrocarbon propane mixtures for the fractionation thereof into oils of higher and lower 70 average molecular weight. Primarily the invention relates to an improved mixing and chilling technique, but since the chilling is of particular importance in the propane dewaxing system its application in that field will be described as a 75 preferred embodiment of the invention.

5 Propane from high pressure storage cylinders 10 may be selectively withdrawn through outlets 11 and lines 12 and 13 by pump 14 to heater 15 and mixer 16. The oil stock is introduced from line 17 by pump 18 which may be driven by the same motor 19 which drives pump 14. Any equivalent means may be employed for proportioning the propane feed with the feed of charging stock. If the charging stock is an S. A. E. 50 Mid-Continent distillate, it may have a pour point of about 135° F., so that it will be introduced into the system at about this temperature. In that case sufficient steam is used in exchanger 15 to warm the propane to substantially an equivalent temperature. Any suitable mechanical mixing means 15 may be employed in mixer 16 and in fact a homogeneous solution of both the oil and wax in the propane may be obtained by warming the mixture to a sufficiently high temperature (usually about 20 80° F. to 140° F.) by means of steam coil 20. Also, we may withdraw liquid from the base of the mixer through pipe 21 and circulate it by pump 22 to the top of the mixer.

25 When a homogeneous mixture has been obtained in mixer 16, we pass the mixture through pipe 23 to heat exchanger or cooler 24 and thence to cooler 25. Cooler 24 is employed to lower the temperature of the mixture to a point slightly below its cloud point, but not low enough to produce solidification of appreciable amounts of wax or the accumulation of wax in the exchanger. In some cases it may be desirable to pass the mixture directly from exchanger 24 through pipe 26 to the batch cooler hereinafter described, by-passing 30 entirely indirect heat exchanger 25. Also we may by-pass exchanger 24 and introduce the solution directly from mixer 16 to the batch cooler, or we may pass it through line 27, line 28 and exchanger 35 25 to the batch cooler.

40 Exchanger 25 may be of the indirect type where-in in scrapers or other mechanical means are employed for removing wax from the heat exchange surfaces. For instance, this exchanger may consist of the well known Carbondale chiller in which the propane-oil mixture flows through the center of a tube and the chilling medium flows in a jacket around the outside of the tube, waxy oil being propelled through the tube and scraped from the sides thereof by means of a screw conveyor. This indirect heat exchange means may be designed as a continuous cooler discharging 45 into any one of a plurality of batch coolers, as hereinafter described, or it may itself be a batch cooler. The cooling medium which is introduced through pipe 28 and which is circulated through the jackets or heat exchange devices is preferably cold, dewaxed filtrate. The propane-oil-wax slurry may be chilled in exchanger 24 and/or exchanger 25 from about 80° F. to 30° F. or about 50 60° F. to -30° F., depending largely upon the 55 type of oil undergoing the dewaxing and the nature of the heat exchangers, scrapers, etc.

60 Partially cooled slurry may be filtered at this point or it may be introduced by line 29 into batch cooler 30. Batch cooler 30 is preferably a 65 pressure vessel which has been especially fabricated or treated to withstand low temperatures. If continuous exchangers are employed, we will use a plurality of these batch coolers in rotation. When sufficient solutes have been charged to the 70 cooler 30, the inlet valve is closed and cooling is started by the introduction of cold propane at about -40° F. from storage tank 31 through line 32 and valve 33. This propane is not injected directly into the body of slurry in the base of cooler 75

20, but is introduced on a bubble plate 34, so that propane which is vaporized from the slurry has to bubble through this cold propane before it can be removed from the chiller through pipes 35 or 36. When the propane vapors come in contact with the cold liquid propane on the bubble plate, the vapors are condensed, which in turn causes the liquid propane to be warmed up. The run-down pipe 37 from bubble plate 34 may lead 10 directly to the liquid in the lower part of the chill chamber, but we prefer to employ one or more additional bubble plates 38 and to introduce the liquid from the lower run-down pipe 39 to the body of liquid in the base of the chiller. By the 15 time the liquid propane reaches lower run-down line 38 it is warmed up to approximately the temperature of the oil-wax slurry, so that its introduction in this manner does not cause shock chilling. For some purposes it is desirable to 20 pump propane from plate 38 through line 39A by means of pump 39B into the bottom of the chiller; this reduces the height required and it also provides adequate circulation and agitation in the chill chamber.

25 The removal of vapors from the top of the tower, together with the addition of cold propane, causes a gradual lowering of the temperature. By employing this method of cooling we may maintain a constant diluent ratio or we may 30 constantly increase or decrease the diluent ratio, depending upon the amount of liquid propane introduced through valve 33 as compared with the amount of propane vapors withdrawn through pipes 35 and 36. When we are dewaxing paraffin 35 distillates and/or removing wax which has a tendency to form interlacing crystals and to occlude oil, we find it is desirable to begin the chilling with a relatively small amount of diluent and to introduce the bulk of the diluent just 40 before the filtration step. We have found that most liquid level gauges are inoperative in this apparatus because of the tendency for propane to vaporize in the gauge, the tendency of wax and oil to plug up small openings, etc. We have 45 discovered, however, that the liquid level in a propane storage tank or chiller may be accurately indicated at all times by means of an internal float designed to operate an indicator through a magnetic clutch. The "Tagliabue" liquid level 50 indicator is of this type; the float is operatively connected to a rotating magnetic core which may be a block of magnetized iron and the rotation of this magnetic core causes the actuation of magnetic indicator means outside of the vessel. 55 We may use such a liquid level control for automatically controlling the amount of propane which is introduced through valve 33. Excellent filter rates can be obtained when the chilling of the wax is effected in this concentrated solution 60 which is maintained substantially uniform by the use of a float control device for regulating the amount of incoming propane.

When the slurry has been chilled to about 65 -40° F. it may be withdrawn from the base of the chiller and introduced by means of pipe 41 and pump 42 to storage tank 43 which acts as a feed supply for the filters. Slurry is pumped from this feed supply through line 44 by pump 45 to filters 46 which may be of the multiple batch 70 type, but which are preferably of the continuous rotary type. When the chilling has been effected in a cocentrated solution, we may add additional cold propane through lines 42 and 47 to the inlet side of pump 42, or through lines 42 and 47a to 75 the inlet side of pump 45. We prefer to filter with

about 2 to 4 volumes of propane per volume of oil. Filtrate is withdrawn through lines 48 and collected in tank 49. The wax cake is withdrawn through conduits 50 to wax pot 51 which acts as a surge tank or reservoir for feeding the wax recovery system, the waxy mixture being forced by pump 52 through line 53 into high pressure still 54 and then being passed through pipe 55 and pressure release valve 66 to low pressure still 57. Wax is withdrawn from the system through pipe 58.

We prefer to maintain a low pressure gas line 59 connected to the intake side of holding compressor 60 which discharges the compressed propane through condenser 61 and pipe 62 to propane storage tanks 10. Cold propane storage tank 31 is connected to the low pressure line through pipe 63, the chiller is connected thereto through pipe 64, filtrate storage means through pipe 65, low pressure wax still through pipe 66, etc.

Also, we may utilize a high pressure gas line 67 which leads through condenser 68 back to storage tanks 10 and which usually requires no compressors although compressor 69 may be used if necessary. High pressure wax still 54 is connected by pipe 70 to the high pressure gas line 67. Wax surge tank 51 may be connected either to line 67 through pipe 71 or line 69 through pipe 72; thus we may warm up the wax in this tank by condensing high pressure propane vapors 30 therein instead of using a heater in the tank.

Filtrate from surge tank or receiver 49 is passed through line 73 by pump 74 to line 28 for cooling the incoming propane-oil-wax mixture. Part or all of the filtrate may also be passed by pipe 75 to heat exchanger 76 for cooling the propane in pipe 77 which is flowing to cold propane reservoir 31.

The propane-filtrate mixture which has been warmed by heat exchange as hereinabove described is introduced by pipe 28 into high pressure filtrate still 78 which is vented by line 79 to high pressure gas line 67. The liquid from this still is passed through line 80 and pressure reducing valve 81 to low pressure filtrate still 82 45 which is vented by line 83 to low pressure propane line 59. Dewaxed oil is removed from the system through line 84.

While we have shown a high pressure and a low pressure gas line, it should be understood 50 that we may also use gas lines of intermediate pressure and that we may connect various units to said gas lines for the regulation of temperatures and pressures. Pipe 16 may be connected to high pressure gas line 67 so that hot propane 55 vapors may be used to warm up the chiller prior to introduction of a charge of waxy oil solution. Filter slurry supply tank 43 is preferably connected to low pressure gas line 59 through pipe 85. Also, the filters may be connected either to 60 the high pressure or the low pressure gas line for the regulation of temperatures and pressures therein.

While we have described in detail a preferred embodiment of our invention, it should be understood that we do not limit ourselves to any of these details except as defined by the following claims which should be construed as broadly as the prior art will permit.

We claim:

1. The method of chilling a solution of waxy oil in propane for crystallizing wax in filterable form which comprises introducing said solution into a closed chilling zone under pressure, introducing cold propane at the upper part of said

- chilling zone, directly contacting said cold propane with propane vapors from said solution whereby the heat of condensation warms up the incoming propane before it is admixed with the propane solution in the lower part of the chilling zone and admixing introduced propane with the solution in the lower part of the chilling zone.
2. The process of claim 1 which includes the step of removing propane vapors from the upper part of said zone.
3. The method of chilling a propane solution of waxy oil for the production of filterable wax crystals which comprises introducing the solution into a closed chilling zone, withdrawing propane vapors from the top of said chilling zone, introducing cold liquid propane near the top of said chilling zone, directly contacting said cold propane with propane vaporized from said solution whereby the introduced propane is brought into temperature equilibrium with the solution before it is admixed therewith, admixing the introduced propane with the solution in the chilling zone and regulating the amount of propane introduced and the amount of propane withdrawn to maintain the optimum diluent ratio.
4. The method of chilling a propane solution of waxy oil containing natural wax crystallization regulators for the preparation of filterable wax crystals which comprises introducing a solution of waxy oil in less than an equal volume of propane into a chilling zone, withdrawing propane vapors from the top of said chilling zone, introducing cold propane near the top of said chilling zone, intimately contacting the propane vapors in said zone with the introduced cold propane whereby the latter is brought into temperature equilibrium with the propane solution prior to admixture thereto, admixing the introduced propane with said solution, and regulating the rate of introducing and removing propane to maintain the propane ratio of the solution less than 1 to 1 by volume until the wax has been solidified in filterable form.

5. The method of chilling a propane solution of waxy oil dissolved in about an equal volume of propane at a relatively high temperature, which comprises partially cooling said mixture by indirect heat exchange, introducing the partially cooled solution into a closed chilling zone, vaporizing propane from the solution in said chilling zone, introducing cold liquid propane at the top of said chilling zone out of contact with the solution therein, condensing propane vapors in the cold liquid propane to bring it into temperature equilibrium with the propane solution, introducing the warmed propane into the solution in the lower part of the chilling zone, and removing propane vapors from the top of said chilling zone at a rate to maintain the ratio of propane to waxy oil at about 1 to 1 during the refrigeration thereof.
6. The method of chilling a solution of waxy oil in propane for crystallizing wax in filterable form which comprises introducing said solution into a closed chilling zone under pressure, vaporizing propane from said solution and removing propane vapors from said zone, introducing cold propane at the upper part of said zone and from the upper part into the solution in the lower part of said zone at substantially the same rate that the propane is removed therefrom so that the liquid level in said zone will remain substantially constant, and directly contacting said cold propane with propane vapors from said solution in the upper part of said zone whereby the heat of condensation warms up incoming propane before it is admixed with the propane solution in the lower part of said zone.
7. The method of claim 6 wherein propane which has been warmed in the upper part of the chilling zone is injected in the lower part of the chilling zone to supply agitation therein.
